UNITED STATES PATENT OFFICE.

WILLARD R. WALKER, OF SYRACUSE, NEW YORK.

DESIGN FOR A DISH-WASHER TANK.

51,447.

Specification for Design.

Patented Oct. 30, 1917.

Application filed July 28, 1916. Serial No. 111,949. Term of patent 14 years.

To all whom it may concern:

Be it known that I, WILLARD R. WALKER, a citizen of the United States, residing at 222 Markland avenue, Syracuse, New York, have invented a new, original, and ornamental Design for Dish-Washer Tanks, of which the following is a description, reference being had to the accompanying drawing, forming a part thereof.

The figure is a perspective view of a dish-washer tank showing my new design.

What I claim is:

The ornamental design for a dish-washer tank as shown.

WILLARD R. WALKER.
